MEDICINAL STEAM VAPORIZER OR THE LIKE

Lawrence Katzman, 11 Riverside Drive, New York, N.Y.,
and Monte L. Levin, New York, N.Y.; said Levin
assignor to Kaz Manufacturing Co., Inc., New York,
N.Y., a corporation of New York

Filed Nov. 13, 1963, Ser. No. 77,415

Term of patent 14 years

(Cl. D83—1)

FIG. 1.

FIG. 2.

FIG. 6.

FIG. 1 is a front elevational view of a medicinal steam vaporizer or the like embodying our new design;

FIG. 2 is a side elevational view thereof, the opposite side being identical with the side shown;

FIG. 3 is a rear elevational view thereof;

FIG. 4 is a top plan view thereof;

FIG. 5 is a bottom plan view thereof;

FIG. 6 is a front perspective view thereof, as seen from FIG. 1.

We claim:

The ornamental design for a medicinal steam vaporizer or the like, as shown.
